FIG. 1. FIG. 2.

FIG. 3. FIG. 4.

FIG. 5.

Inventor

Francois Courtinade,
By his Attorneys

Edgar V. & C.

UNITED STATES PATENT OFFICE.

FRANÇOIS COURTINADE, OF NEW YORK, N. Y.

CIGARETTE.

1,257,815.

Specification of Letters Patent. Patented Feb. 26, 1918.

Application filed March 8, 1917. Serial No. 153,228.

To all whom it may concern:

Be it known that I, FRANÇOIS COURTINADE, a citizen of France, and residing at New York, in the county of New York and State 5 of New York, have invented certain new and useful Improvements in Cigarettes, of which the following is a specification, such as will enable those skilled in the art to which it appertains to make and use the same.

10 This invention relates to cigarettes and particularly to the means for reinforcing, strengthening and decorating such articles, and the invention consists in a cigarette or cigarettes made as hereinafter described and

15 claimed and in the wrapper or wrappers employed in the manufacture of such cigarette or cigarettes.

The invention is fully disclosed in the following specification, of which the accompanying drawing forms a part, in which the separate parts of my improvement are designated by suitable reference characters in each of the views, and in which:—

Figure 1 is a side view of a cigarette, the 25 wrapper of which is made and applied according to my invention;

Fig. 2 a similar view showing a modification;

Fig. 3 a plan view of the wrapper employed in forming the cigarette shown in 30 Fig. 1;

Fig. 4 a similar view of the wrapper employed in making the cigarette shown in Fig. 2; and,

Fig. 5 another view of the cigarette shown in Fig. 2 but showing an additional feature of my invention.

In the practice of my invention, as shown in Figs. 1 and 3, I provide a wrapper *a*, said 40 wrapper being composed of the usual material, and one side edge portion thereof is provided with projecting strips *a*², three of which are shown, and any desired number of which are employed, and these strips are 45 gummed on their inner sides as shown at *a*³, and in the use of this wrapper, in the operation of making a cigarette *c* shown in Fig. 1, the cigarette is rolled in the usual manner and the side edge *a*⁴ of the wrapper overlaps 50 the side edge *a*⁵ as shown, and said strips extend or are passed entirely around the cigarette, and the free end portions thereof overlap and are sealed to the base end portions thereof as shown at *a*⁶ in said figure.

55 In forming the wrapper shown in Fig. 4 and which is used in the making or forma-

tion of the cigarette *d* shown in Fig. 2, the strips *a*² are made V-shaped in form at the base thereof or where they connect with the side edge portion of the wrapper, or said 60 strips are provided with V-shaped base portions in which are formed V-shaped openings *a*⁷, and in the operation of forming the cigarette the free end portions of said strips extend or are passed entirely around the 65 wrapper and are sealed to the edge portion *a*⁴ of the wrapper as shown at *a*⁸ in Fig. 2, or the end portions of the strips *a*² may be carried over and sealed to the side edge portion 70 *a*⁵ of the wrapper.

From the foregoing description it will be seen that the only difference in the form of the wrapper, or in the appearance of the cigarette produced, is in the number and form of the strips *a*², and my invention is 75 not limited to the number of said strips employed, nor to the form thereof, and it will also be seen, or understood, that with my improvement the edge portion *a*⁴ of the wrapper is not necessarily sealed to the opposite 80 side edge portion *a*⁵ which it overlaps, and the wrapper may only be held in position and the cigarette retained in proper form by means of the strips *a*², but my invention is not limited to this idea and the side edge 85 portions *a*⁴ and *a*⁵ of the wrapper may be overlapped and sealed together in the usual manner, if desired.

In Fig. 5 I have shown the cigarette *d* of Fig. 2 provided with an additional element 90 of reinforcement and decoration which consists of a thin narrow ribbon or a strip *e* which is passed around the mouth end portion of the cigarette, or that end portion which is intended to be placed in the mouth, 95 in the operation of smoking, and formed into a bow *e*².

It will be observed that the strips *a*² of the wrapper or wrappers employed extend at right angles to said wrapper or wrappers, 100 but this direction of said strips is not necessary and said strips may project or extend at any desired angle or angles from the side edge portions of the wrapper with which they are connected.

105 The method of making the cigarette herein described is also of my invention but is not claimed herein, said method being made the subject of a companion application for Letters Patent of the United States prepared 110 and filed by me of equal date herewith.

Having fully described my invention, what

I claim as new and desire to secure by Letters Patent, is:—

1. A wrapper for cigarettes one side edge portion of which is provided with reinforcing, strengthening and decorating strips which are passed around the cigarette in the operation of forming the same and are sealed thereto.
2. A wrapper for cigarettes one side edge portion of which is provided with reinforcing, strengthening and decorating strips

which are passed around said wrapper and sealed thereto.

In testimony that I claim the foregoing as my invention I have signed my name in 15 presence of the subscribing witnesses this 7th day of March 1917.

FRANÇOIS COURTINADE.

Witnesses:

C. E. MULREANY,
V. E. THOMPSON.
